CABLE GUARD

Filed Feb. 13, 1928

Inventor

H. W. Baum

By Clarence A. O'Brien, Attorney

UNITED STATES PATENT OFFICE

HOWARD W. BAUM, OF KEARNY, NEW JERSEY

CABLE GUARD

Application filed February 13, 1928. Serial No. 253,985.

The present invention relates to a hoisting apparatus and has for its prime object to provide improvements for enhancing the simplicity, ease of operation and manipulation, and efficiency and reliability of operation of said apparatus.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the hoisting apparatus.

Figure 2 is a detail section taken substantially on the line 2—2 of Figure 1.

Referring to the drawings in detail it will be seen that the numeral 5 generally refers to a derrick structure.

The guide structure which makes up the present invention comprises a bracket 50 mounted on the end of the derrick beam and having journally mounted therein sheaves 51 over which the cables 39 are trained. A hood shaped casting 53 is attached to the bracket 50 to swing on the axis of the sheaves 51, and has detachably fixed in the lower end thereof a guide bushing 54 which has two openings therein as shown in Figure 2 and specifically denoted by numerals 55 through which the cables 39 pass. This bushing is held in place by means of a set screw 56. The upper end of the casting extends over the sheaves 51 to act as a hood therefor. A guide 57 is provided for the iron steel bucket.

It is thought that the construction, operation and advantages of this invention will now be clearly understood without a more detailed description thereof.

The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing

from the spirit or scope of the invention as hereinafter claimed or sacrificing any of its advantages.

Having thus described my invention, what I claim as new is:

A cable guard of the character described comprising a bracket, a sheave mounted within the bracket, a vertically disposed hood pivotally secured to the bracket within which the sheave is mounted, said hood partly surrounding the sheave and being provided with a tubular depending portion, a bushing for disposition within the lower portion of the hood, and means for securing the said bushing in position.

In testimony whereof I affix my signature.

HOWARD W. BAUM.
